UNITED STATES PATENT OFFICE.

ROY HARTWELL, OF MARION, ILLINOIS.

BOILER-TUBE BLOWER.

1,115,533.

Specification of Letters Patent.

Patented Nov. 3, 1914.

Application filed November 6, 1912. Serial No. 729,805.

To all whom it may concern:

Be it known that I, ROY HARTWELL, a citizen of the United States, residing at Marion, in the county of Williamson and State of Illinois, have invented certain new and useful Improvements in Boiler-Tube Blowers, of which the following is a specification.

My invention relates to a device for cleaning boiler tubes, by blowing steam or compressed air through the same.

An important object of this invention is to provide a device of the above mentioned character, which may be bodily supported and readily handled by a single operator, who inserts the nozzle of the device in the ends of the different boiler tubes.

A further object of the invention is to provide a device of the above mentioned character having a control valve which is automatically returned to its seat or closed position by the pressure of the compressed air or steam, whereby as soon as the manually operated control lever is released, the supply of compressed air or steam will be instantaneously cut off, thus preventing the steam or soot from being blown back upon the operator when the nozzle of the device is being removed from within the end of the boiler tube.

A further object of my invention is to provide a nozzle of improved construction, which will deliver a circumferentially enlarged stream of compressed air or steam, so that the same will completely fill the boiler tube to act upon the inner wall thereof for the purpose of thoroughly removing the soot or other deposits.

A further object of this invention is to provide a device of the above mentioned character, which is simple in construction, cheap to manufacture, strong and durable.

Other objects and advantages of the invention will be apparent during the course of the following description.

In the accompanying drawings forming a part of this specification and in which like numerals are employed to designate like parts throughout the same, Figure 1 is a central vertical longitudinal sectional view through the device, parts thereof being shown in elevation, and, Fig. 2 is an end view of the discharge end of the nozzle.

In the drawings wherein for the purpose of illustration, I have shown a preferred embodiment of my invention, the numeral 3

designates a tubular body portion, having an extension or casting 4 formed upon one end thereof. Connected with the extension 4 is a preferably tubular handle 5, the same having screw-threaded engagement therewith, as shown. Connected with the tubular body portion 3 and the extension 4 and preferably cast integral therewith, is a supply pipe 6, which is spaced from the tubular handle 5 and parallel thereto, as shown. Suitably connected with the free end of the supply pipe 6 is a hose or conduit 7, which has connection with a source of compressed air or steam (not shown). The tubular body portion 3 is provided with a screw-threaded tubular extension 8, having connection with a tubular shank 9, carrying a loop-handle 10, as shown.

The numeral 11 designates the outer shell 75 of a nozzle, which shell is conical and increases in diameter toward its free end, as shown. This main shell is constructed of a suitable diameter to properly fit within the end of the boiler tube. At its reduced 80 end the shell 11 is screw-threaded, as shown, for connection with a coupling 12, which has screw-threaded engagement with the forward end of the tubular body portion 3. Disposed concentrically within the main 85 shell 11 and suitably spaced upon the inner wall thereof is a conical deflector 13, which increases in diameter toward the large end of the shell 11. This conical deflector 13 is preferably formed hollow and is connected 90 with the shell 11 by means of radially disposed webs 14, as shown. The function of constructing the outer shell 11 and deflector 13 conical with their diameters increasing toward the outer or free ends thereof, is to 95 provide means to spread or circumferentially increase the size of the stream of compressed air or steam, whereby the same will completely fill the diameter of the boiler tube and properly engage the inner wall 100 thereof to thoroughly remove the soot or other deposits found thereon.

Connected in the supply pipe 6 is a self-closing valve structure, comprising a valve shell 15 divided into two chambers by a 105 transverse web 16, having an opening 17, the walls of which serve as a valve seat for a reciprocating valve 18. The valve 18 is carried by a reciprocating stem 19, which is mounted through an apertured boss 20, as 110 shown. The boss 20 is screw-threaded for engagement with a cap 21, which provides

a chamber 22 for receiving packing, to prevent any leakage about the stem 19. At its opposite end the stem 19 operates within an opening formed in a plug 23, having screw-threaded engagement with the shell 15, as shown. A spring 24 surrounds the stem 19, and is confined between the valve 18 and the plug 23. It is thus seen that the spring 24 urges the valve 23 into engagement with its seat. The valve stem 19 extends outwardly beyond the cap 20, and is engaged by one end of a pivoted operating lever 25, which is mounted upon a bracket or extension 26, carried by the supply pipe 6, as shown.

15 The operation of the device is as follows:—The operator takes hold of the handle 10 with his left hand and the handle 5 with his right hand, and inserts the shell 11 in the boiler tube to be cleaned. The operating valve 18 being closed, the compressed air or steam in the supply pipe 6 will tend to hold the same closed and will tend to return the same to its closed position, when moved therefrom. Without taking his right 25 hand off of the handle 5, the operator places his fingers upon the operating lever 25 and swings the lower end thereof toward the handle 5. The valve 18 is thus unseated, whereby the compressed air or steam is fed 30 through the tubular body portion 3 and discharges from the nozzle into the boiler tube. As soon as the control lever 25 is released, the spring 24 and the pressure within the supply pipe 6, will instantaneously close or 35 seat the valve 18, thus cutting off the supply of compressed air or steam, whereby when the nozzle is removed from within the boiler tube, the steam or soot will not be blown upon the operator. It is thus seen that I 40 have provided a self-closing valve structure, which is operated by a manually moved control lever, disposed in a convenient position with relation to the handle 5, whereby such

control lever may be moved without releasing such handle. The nozzle is so constructed 45 that it spreads or circumferentially increases the size of the stream of compressed air or steam, whereby such stream will properly engage the inner wall of the boiler tube.

It is to be understood that the form of 50 my invention herewith shown and described, is to be taken as a preferred example of the same and that certain changes in the shape, size and arrangement of parts may be resorted to without departing from the spirit 55 of the invention or the scope of the subjoined claim.

Having fully described my invention, I claim:—

The combination with a tubular body portion having a tubular lateral extension, of a nozzle attached to the free end of the tubular body portion and adapted for insertion in the tubes of a boiler and to be removed therefrom, a flexible pressure supply pipe 60 connected with the tubular lateral extension, a self-closing valve connected in the tubular lateral extension, a lever pivoted with the tubular lateral extension and extending longitudinally of the same and 65 adapted to open the valve when its free end is moved away from the tubular lateral extension, a laterally extending handle connected with the tubular body portion outwardly of the tubular lateral extension and having the free end of the lever disposed adjacent the same, and a second laterally extending handle connected with the tubular body portion between the nozzle and the tubular lateral extension. 70

In testimony whereof I affix my signature in presence of two witnesses.

ROY HARTWELL.
